[57] CLAIM

The ornamental design for a telephone instrument or
similar article, as shown and described.

DESCRIPTION

FIG. 1 is a front elevational view of a telephone instrument or similar article showing my new design;
FIG. 2 is a side elevational view thereof, partly in perspective, taken from the right-hand side of FIG. 1;
FIG. 3 is a top plan view thereof; and
FIG. 4 is a rear elevational view thereof.

FIG 1

FIG 2

FIG 3

FIG 4
